UNITED STATES PATENT OFFICE.

ANDREW AMBROSE WENSINGER, OF TOLEDO, OHIO.

DESIGN FOR A SOUVENIR-BUTTON.

SPECIFICATION forming part of Design No. 32,271, dated February 27, 1900.

Application filed June 9, 1899. Serial No. 719,974. Term of patent 31 years.

To all whom it may concern:

Be it known that I, ANDREW AMBROSE WENSINGER, a citizen of the United States, residing at Toledo, Lucas county, State of Ohio, (my post-office address being 911 Cherry street,) have invented and produced a new and original Design for a Souvenir-Button, of which the following is a specification, reference being had to the accompanying drawings, forming a part hereof.

Figure 1 is a view of a souvenir-button, enlarged, showing my design; Fig. 2, a sectional view taken at the line X X of Fig. 1.

As shown in the drawings, the leading or material feature of my design consists of a frog seated in an upright position in an open

buckeye-bur, the whole engraved or otherwise ornamented.

It is apparent that this design is applicable to both clasp-buttons and studs and may be engraved on spoons, ladies' belt-buckles, watch-charms, and other ornaments.

Having described my invention, what I claim as new, and desire to secure by Letters Patent, is—

The design for a souvenir-button, as herein shown and described.

ANDREW AMBROSE WENSINGER.
